UNITED STATES PATENT OFFICE.

FERDINAND J. HOHNHORST AND FERDINAND J. KROEGER, OF COVINGTON, KENTUCKY.

MECHANISM FOR TRUING AND DRESSING GRINDING WHEELS.

Application filed June 15, 1925. Serial No. 37,080.

Our invention relates to mechanism for truing and dressing grinding wheels, such as emery wheels employed in machinery for grinding or polishing surfaces of metal in 5 precision grinding, and is exemplified as employable for truing or dressing the grinding wheel without removing the grinding wheel from the grinding or polishing machine.

Our invention is an improvement for simplification upon the devices shown, described and claimed in our Letters Patent No. 1,526,496, dated February 17, 1925, and our copending applications for patents respectively filed in the United States Patent Office 15 on January 30, 1925, as Serial No. 5707, and on February 16, 1925, as Serial No. 9412, all on improvements in mechanism for truing and dressing grinding wheels.

We have found that in precision grinding 20 or polishing, it is essential for obtaining best results that the grinding wheel shall be maintained in its true form, for instance, cylindrical form, and that for accomplishing this, it is advisable to employ an abrading wheel 25 located at an angle with relation to the plane of the grinding wheel, and to so mount the abrading wheel that vibrations thereof during the grinding or polishing are avoided, and to provide a mounting for the abrading 30 wheel so constructed and arranged that its parts are simple, strong and durable, and are capable of being quickly replaced for repair and renewal of the parts, features especially important in rapid reproduction work 35 as, for instance, in the automobile field.

It is the object of our invention therefore to provide a novel truing and dressing device of this character and having the advantages 40 stated.

It is the object of our invention, further, to provide an abrading wheel rotatable upon a plurality of sets of ball-bearings, each of 45 which sets comprises radially and oppositely disposed end thrust ball-bearings, and projecting the respective sets of ball-bearings within the abrading wheel between the planes of the sides of the latter; further, to provide novel means for mounting the ball-bearings so that the same may be readily and quickly 50 removed; and, further, to provide novel means for clamping the axle which supports the ball-bearings and abrading wheel and the projecting guard for the abrading wheel in place for quick attachment and removal.

The invention will be further readily understood from the following description and

claim, and from the drawings, in which latter:

Fig. 1 is a plan view of our improved device applied to an exemplified grinding machine, partly broken away. 60

Fig. 2 is a cross-section of the same, taken on the line 2—2 of Fig. 1, and partly broken away.

Fig. 3 is a plan view of the abrading wheel 65 and its mounting.

Fig. 4 is a vertical axial section of the same, taken on the line 4—4 of Fig. 3; and,

Fig. 5 is a vertical section of the same, taken on the line 5—5 of Fig. 3. 70

We have exemplified our invention as employed in connection with a so-called grinding or polishing machine employing a rotary grinding wheel 11 for effecting the grinding or polishing. 75

The work to be ground or polished, which may for instance be a shaft, is arranged to be placed between suitable centers 12, 13, of which 12 may exemplify a head-center, arranged to be rotated by suitable driving means, as by a pulley 14. A usual quill 15 in which the head-center is supported in usual manner is journaled in a bearing 16 of a headstock 17, slideable laterally on guideways 18, 19, of a table 20. 80

The tail-center 13 is mounted in a suitable sleeve 21, movable axially in a bearing 22, in usual manner, the bearing being on a tailstock 23 laterally adjustable on the guideways 18, 19, of the table 20. 85

The table is exemplified as pivotally mounted by a pivot 25 on a saddle 26, which has lateral reciprocating motion imparted thereto by power means, in usual manner, as by a pinion 27, suitably driven, meshing with the rack 28 extending lengthwise of the saddle and fixed to the saddle. The saddle is slideable on guideways 29, 30, on the frame 31 of the machine. 90

The grinding wheel 11 is suitably fixed to a shaft 34 journaled in bearings 35 of a slide 36, adjustable toward and from the work-table on guideways 37, by any suitable means, the slide being arranged to be clamped by means of suitable T-bolts and nuts 38, the heads of the T-bolts coating with the T-slot 39 in the frame, and the nuts clamping the slide to the frame. The shaft is rotatable in suitable manner, as by a belt passing about suitable pulleys 40, 41, fixed to the shaft. 100

In the exemplification, the work located between the centers may be caused to reciprocate 110

axially in planes parallel to the axis of rotation of the grinding wheel for grinding or polishing straight work, or the table may be adjusted to an angle with relation to said parallelism, effected, for instance, by rotation of the handle 42 according to the reading on the gage 43.

We have in the present exemplification illustrated a reciprocating table on which to mount the work, the grinding wheel having a stationary position, although the relation of the parts may be reversed, the work being stationarily positioned and the grinding wheel having reciprocations imparted to it. 10 15

15. We have instanced the abrading parts as acting on the grinding wheel in the absence of work between the centers. The grinding machine may be of any desirable construction.

The rotary abrading part is exemplified as 20 in abrading wheel 45. The abrading wheel is preferably of a texture much harder than the grinding wheel and of smaller diameter than the diameter of the grinding wheel on which it operates. The rotation imparted 25 to the grinding wheel is instanced as in the direction of the arrow *a*, while the rotation imparted to the abrading wheel through the medium of the grinding wheel is instanced as in the direction of the arrow *b*. The abrading wheel is normally quiescent, and rotation is imparted to it by the rotation of the grinding wheel with which it is placed in contact during the truing or dressing operation.

The grinding wheel during operation becomes impregnated with particles of dirt or metal from the work being operated on, and becomes comparatively glossy and thereby loses its grinding effect, its granular structure also becoming dull at the grinding face, 35 thereby reducing its grinding or polishing properties.

By means of our invention, particles of dirt and metal are removed from the grinding surface of the grinding wheel by coaction of 40 the rotary abrading wheel therewith, with the plane of the abrading wheel preferably located at an angle to the plane of the grinding wheel, whereby to clear the recesses and pores in the grinding surface, and for sharpening the particles or grains in the abrading surface, by endwise passage between the grinding wheel and the abrading wheel while at angular relations with each other and in contact with each other.

45 A swirling action of the abrading surface of the abrading wheel upon the grinding surface of the grinding wheel is thereby produced in order to clean the interstices or pores of the grinding wheel by brushing out the particles of dirt or metal which may be lodged therein. The more nearly parallel the plane of the abrading wheel is to that of the grinding wheel, the finer will be the dressing imparted to the grinding wheel, and the greater 50 such angle is, within limits for producing

proper rotation of the abrading wheel by the grinding wheel, the coarser will be the dressing imparted to the grinding wheel. The fineness and coarseness of dressing is controlled by the angle at which the abrading wheel is placed with relation to the grinding wheel. 70

An axle 51 is stationarily positioned. It is shown as extending laterally from a shank 52, and is fixed thereto, accomplished in the present instance by providing said axle with a tapered end 53, received in a correspondingly tapered bearing 54 in the end of the shank. 75

This bearing is exemplified as a clamp bearing, being provided with a split 55 and a bolt 56 and nut 57 for drawing the cheeks of the bearing thus formed toward each other, in order to clamp the axle in said bearing. The axle may also be provided with a threaded end 58, about which a nut 59 is received, for drawing the tapered end of the axle in axial direction into the bearing for additionally securing the same in place. 80 85

A pair of sets of ball-bearings 61, 62, are 90 received about the axle. Each of these sets of ball-bearings comprises a plurality of ball-bearings, which are combined radial and end thrust bearings, the end thrust portions of the same being projected in opposite directions. 95

Thus each set of ball-bearings comprises a double inner raceway 63, and a pair of outer raceways 64, 65, having a series of balls 66, 67, coacting therewith. The inner raceways 100 are exemplified as provided with annular runways 68, 69, for the balls. The outer raceways are exemplified as having oppositely projected end thrust annular rabbets 70, 71, in which the balls are located. 105

There is a collar 75 about the axle, between the inner raceways of the respective sets of raceways. This collar is preferably axially fast on the axle.

There is a spacing-ring 76 between the 110 outer raceways of the respective sets of raceways.

A shell 81 is received about the ball-bearings. This shell is provided with an inwardly projecting annular flange 82 at one end 115 thereof, this flange being provided with an annular shoulder 83. The ball-bearings are received in the bore of the shell. The other end of the shell is provided with a threaded inner periphery 84, to which a plug 85 is 120 threaded. The inner end of the plug is provided with an annular shoulder 86, and is also provided with sockets 87 for a suitable spanner wrench.

The outer raceways of the respective sets of ball-bearings and the spacing-ring 76 therebetween are clamped in endwise relation between the shoulder 83 and the plug 85. 125

The inner raceways of the respective sets of raceways are received closely about the 130

axle, with the collar 75 therebetween. The inwardly extending flange 82 of the shell is provided with a central hole 88, through which the axle is received, the axle preferably having close connection with the wall of said hole in order that the interior of the shell may form a lubricant cavity 89.

The said flange is also provided with an inner annular recess 91 and the plug is provided with an inner annular recess 92. These recesses permit just sufficient end play between the inner raceways and outer raceways to prevent binding between said raceways and the balls therebetween, but hold the abrading wheel in endwise relation on the axle.

The plug 85 closes the end of the shell and may be provided with a central recess 93 so as to avoid danger of contact between the end 20 of the axle and said plug.

The lubricant, for instance, oil or light grease, may be supplied through a passage 94 in the axle. This passage is exemplified as a central bore extending through the axle 25 and discharging into the cavity into the shell at one end and arranged to receive the lubricant through its other end. This other or outer end of the axle may, if desired, be provided with a threaded recess 95 to which a 30 suitable force feed pipe for a lubricant may be attached, and which may be closed by a suitable plug 96 after the lubricant has been supplied.

The shell is also provided with an outwardly extending annular flange 97. The other end of the shell may be threaded at its outer periphery, as shown at 98, for receiving a nut 99 thereover, for clamping the abrading wheel 45 in place. A washer 100 may be interposed between the abrading wheel and the nut, and the abrading wheel and said nut clamped between the outwardly extending flange 97 and the nut 99.

A protecting guard 101, which partly encompasses the abrading wheel, may be provided. It is shown as having flanges 102, 103, at the respective sides of the abrading wheel, and a top 104 connecting said flanges. Lugs 105, 106, are shown provided for securing the guard in place, effected for instance by a bolt 107 received through a hole in the lug 105 and threaded into the shank. The bolt 56 is shown extending through a hole in the lug 106, this lug being clamped in place simultaneously with the clamping of the clamp-bearing 54. The part of the shank to which the axle and the guard are secured, is shown square, forming a head 108, and the shank is shown cylindrical, so that it may be turned in its securing means for locating the plane of the abrading wheel in desired relation to the plane of the grinding wheel.

The shank 52 is of heavy and substantial nature, and is arranged to be rigidly secured 65 in place on the grinding machine. The ex-

amplified means for fixing the shank in place comprise the following instrumentalities: The table of the grinding or polishing machine is provided with a guide 111 and a rail 112. A clamp 113 is provided with a jaw 114 co-acting with the guide, and a clamping means, the latter comprising a jaw 116 having an inclined face 117 on the body of the clamp and a clamp-plate 118, the inclined face and the clamp-plate being arranged to clamp upon 75 the rail 112.

A stem 121 is located in the bearing 122 of the clamp. An adjusting nut 125 and a lock nut 126 are received over the threaded end 127 of said stem. Said stem is provided with 80 a flattened head 129, a fork 130 of a handle 131 being received about said head and articulated therewith by means of a pin 132.

The head 129 is received through a slot in a cap 136. The inner end of the fork 130 is 85 provided with cams 139 and shoulders 140 at the respective sides of the flattened head 129. These cams and shoulders are arranged to bear against the cap, and to cause clamping movement between said cap and the 90 clamp-plate 118 at one side of the rail 112 and the inclined face 117 at the other side of said rail, causing clamping of the jaw upon said rail.

The body of the clamp is provided with a 95 bearing 145, shown as a clamp-bearing, in which the shank 52 is received and rigidly held, the clamp-bearing being clamped to the shank by means of bolts 146, received through holes of a cheek 148, and threaded in threaded 100 holes of a cheek 150, the cheeks being located at the respective sides of the split 151 in said clamp-bearing, which is thereby constituted a split-bearing. The shank may be rotatively positioned in the bearing 145 for presenting the abrading wheel in a plane at the desired angle to the plane of the grinding wheel, dependent on the character of truing, dressing or polishing to be accomplished, and the shank clamped in said bearing in such relation.

If desired there may be an abrading wheel at each side of the shank 52, the said abrading wheels arranged in angular relation to each other, as disclosed in the aforesaid patent and applications.

It has been found that in machines of this character, especially in machines employed in intensive grinding as in the automobile field, the parts are subjected to rapid wear, 120 and that the abrading wheel is subjected to great end strains, and that the operation of the abrading wheel takes place in the presence of the abrasive refuse from the abrading wheel and the grinding wheel, all of which 125 tend to create quick wear in the parts of the abrading device.

In order to minimize such wear, and to provide an abrading device in which the parts are quickly repaired or renewable, and to pro-

vide a device in which tortional or tilting strains upon the abrading wheel are resisted to greatest extent, and chattering of the abrading wheel is avoided; we have provided 5 the means herein shown and described, wherein the abrading wheel rotates about a plurality of sets of ball-bearings, with the respective sets of ball-bearings projected within the bore of the abrading wheel, so that the abrading wheel shall have long bearings, and so that endwise and tilting strains on the abrading wheel may be resisted by a plurality of end thrust ball-bearings, projected in opposite directions, and further, provide means 10 whereby ball-bearings are enclosed, and whereby lubrication of the same is readily provided, and so arranged that the oil or lubricant therein will also arrest the passage of abrading dust and dirt thereinto.

15 20 Having thus fully described our invention

what we claim as new, and desire to secure by Letters Patent, is:

In mechanism for truing and dressing grinding wheels, the combination of a shank, a clamp-bearing at one end thereof, an axle 25 in said clamp-bearing and extending laterally from said shank, a shell about said axle, ball-bearings between said shell and said axle, an abrading wheel secured to said shell, a safety-guard partly encompassing said abrading 30 wheel, and bolts securing said safety-guard to said shank, one of said bolts received through said clamp-bearing and a part of said safety-guard for simultaneously clamping said bearing and said safety-guard. 35

In testimony whereof, we have hereunto signed our names.

FERDINAND J. HOHNHORST.

FERDINAND J. KROEGER.
